UNITED STATES PATENT OFFICE.

FRANCESCO CIRELLI, OF PHILADELPHIA, PENNSYLVANIA.

SOUND-BOX.

1,314,127.

Specification of Letters Patent. Patented Aug. 26, 1919.

Application filed August 6, 1918. Serial No. 248,557.

To all whom it may concern:

Be it known that I, FRANCESCO CIRELLI, a subject of the King of Italy, residing at Philadelphia, in the county of Philadelphia, 5 and State of Pennsylvania, have invented certain new and useful Improvements in Sound-Boxes, of which the following is a specification.

One object of my invention is to so construct an improved sound box for sound reproducing machines that a record-engaging needle can be secured thereto in such manner as to permit the needle to engage the sound reproducing grooves of the record 15 from either side of the center of the record. Thus with the aid of my invention a left handed person can use the same with as much precision and convenience as a right handed person.

Another object is to make my improved sound box in such manner that it can be quickly manufactured and assembled and so that it will be strong and durable.

Another object is to make my improved sound box in such manner that an improved quality of sound will be produced and so that the volume of sound can be varied.

These objects, and other advantageous ends which will be described hereinafter, 30 I attain in the following manner, reference being had to the accompanying drawings in which—

Figure 1 is a front elevation of my improved sound box,

Fig. 2 is a sectional elevation taken on the line 2—2 of Fig. 1,

Fig. 3 is an enlarged sectional plan view taken on the line 3—3 of Fig. 1,

Fig. 4 is a fragmentary elevation of a portion of a ring section which forms a part of my invention,

Fig. 5 is an enlarged fragmentary section taken on the line 5—5 of Fig. 2 through the needle holding end of the stylus bar,

Fig. 6 is a section taken on the line 6—6 of Fig. 5,

Fig. 7 is a front elevation of the needle holding end of the stylus bar,

Fig. 8 is a view of similar nature to Fig. 7, showing a needle therein extending at such angle as to permit its entrance to the sound reproducing grooves from one side of the record,

Fig. 9 is a view of similar nature to Fig. 8, showing the needle therein extending at an angle opposite to that shown in Fig. 8

and in which angle the needle can be inserted into the reproducing grooves of a record from the opposite side of the center thereof,

Fig. 10 is a side elevation of the needle holding end of the stylus bar showing a needle extending at a transverse angle to permit reproduction on certain classes of records, and

Fig. 11 is a top plan view showing in full lines and dot-and-dash lines how my improved sound box can be operated from opposite side of the center of a disk record.

Referring to the drawings, the sound box 12 includes two sections 13 and 14. The section 13 is in the form of a circular plate having a sound outlet hole 15 and a sleeve 16 in alignment therewith, said sleeve forming means of attachment to a tone arm, such for example as the tone arm 17. The section 13 has a circular recess 18 in which fits a gasket 19 preferably made of soft rubber. The section 14 is made in the form of a ring and has a circular recess 20 in which is fitted a gasket 21 also preferably made of rubber 80 and of substantially the same diameter as the gasket 19.

The diaphragm 22 has its peripheral edge portion between the two gaskets 19 and 21 and screws 23 extend through the section 14 85 into tapped holes in the section 13 and thereby serve to clamp the diaphragm between the gaskets 19 and 21. The ring section 14 has a notch 24 in its peripheral edge and this notch has its side portions 25 tapering inwardly to correspond with the outer surface 26 of a ring 27.

This ring 27 is fitted within the notch 24 so that the surface 26 coincides with the surfaces 25 of the notch 24 and a screw 28 95 passes through the ring 27 into a tapped hole 29 of the rear section 13 (see Figs. 2, 3, and 4).

A stylus bar 30 has its upper end connected to the diaphragm 22 and passes downwardly and substantially centrally through the ring 27. The ring 27 has trunnion screws 31 which engage recesses 32 in opposite surfaces of an enlargement 33 on the stylus bar 30.

The ring 27 has a tapped hole 34 of sufficient size to permit a screw-driver to be inserted therethrough in order to insert or remove the screw 28 when it is so desired.

A threaded adjusting screw 35 fits within 110 the tapped hole 34 and is adapted to be moved into engagement with the enlarge-

ment 33 of the stylus bar 30. Pressure is thereby brought to bear upon the stylus bar to vary the volume of the sound.

The screw 35 is provided with a lock nut 36 so as to prevent the vibration from loosening said screw 35 during the operation of the device.

The notch 24 performs two valuable functions. In the first place it forms a secure 10 backing for the ring 27, and in the second place when the ring section 14 is placed in position together with the ring 27 the holes for the grooves 23 will be brought into register. Thus the parts can be quickly assembled.

The needle holding end 37 of the stylus bar 30 is enlarged to provide a top ledge 38 and two ducts 39 and 40 cross each other in the plane of the section 5-5 and have 20 their upper ends opening at the ledge 38 and their lower ends opening onto the bottom surface 41. These ducts 39 and 40 thus extend at an incline to each other in opposite directions.

25 A tapped hole 42 is provided which intersects both of the ducts 39 and 40 and a tightening screw 43 fits the hole 42 and is adapted, when screwed inwardly, to secure a sound reproducing needle 44 in either of 30 the ducts 39 and 40. For example Fig. 8 shows a needle secured in the duct 39 and Fig. 9 shows a needle secured in the duct 40.

Another duct 45 is formed in the needle holding end 37 and slants forwardly and is 35 intersected by the tapped hole 42. Thus a needle positioned within the duct 45 can be secured by the tightening screw 43, as clearly shown in Figs. 6 and 10.

Considering that a record 46 is rotating in 40 the direction of the arrows in Fig. 11 and a needle 44 is inserted within the duct 40, the tone arm 17 can be so positioned as to bring the needle into engagement with the sound transmitting grooves of the record at the 45 right side of the center 47 and the record can thus be played in the usual manner.

If, on the contrary, a needle is inserted within the duct 39 and secured therein by the tightening screw 43, the record can be 50 played by moving the needle into engagement with the grooves at the left of the center 47.

In some makes of records the needle when

extending at an angle forwardly, such for example as when secured within the duct 45, 55 produces the best effect. However, it will be noted that by securing the needle in either of the grooves 39 and 40 a record can be played from opposite sides of the center without changing the direction of rotation 60 of the record.

The volume of sound can be varied by varying the pressure of the screw 36 on the stylus bar 30 and the diaphragm is firmly held between the gaskets so as to give an 65 accurate transmission of the sound.

By having the ducts 39, 40, and 45 open at the ledge 38 various length needles can be used and if desired a portion of the blunt end of the needle can project above the 70 ledge. Thus a very short or long portion of the needle can project beyond the bottom surface 41 and the volume of sound can be regulated by this provision.

While I have described my invention as 75 taking a particular form, it will be understood that the various parts of my invention may be changed without departing from the spirit thereof, and hence I do not limit myself to the precise construction set 80 forth, but consider that I am at liberty to make such changes and alterations as fairly come within the scope of the appended claim.

Having thus described my invention, what 85 I claim as new and desire to secure by Letters Patent is:

A sound box including a needle holding portion having needle retaining ducts extending at an incline to each other in opposite directions whereby a needle can be secured at an incline in either of said ducts so as to permit the engagement of the needle with the reproducing portion of a record at opposite sides of the center of rotation of 95 said record during the rotation of said record in the same direction, substantially as described.

In testimony whereof I have signed my name to this specification in the presence of 100 two subscribing witnesses.

FRANCESCO CIRELLI.
